THOMAS SPENCER MILLER, OF SOUTH ORANGE, NEW JERSEY.

TOWING-ENGINE.

1,319,601.

Specification of Letters Patent.

Patented Oct. 21, 1919.

Application filed June 26, 1917, Serial No. 177,072. Renewed September 6, 1919. Serial No. 322,232.

To all whom it may concern:

Be it known that I, THOMAS SPENCER MILLER, a citizen of the United States, residing at South Orange, in the county of 5 Essex and State of New Jersey, have invented certain new and useful Improvements in Towing-Engines, of which the following is a specification.

My invention relates to new and useful 10 improvements in towing engines, and more particularly of that character or type including a drum upon which the towing hawser is wound or held, and provided with a motor for operating the drum, and provisions for automatically controlling the 15 tension in the towing hawser.

In towing engines of this character or type previous to my invention, and of which I am aware, it has usually been the practice 20 to employ a steam engine for operating and holding the drum, which engine was controlled by the motion of itself and its drum and drum shaft geared or otherwise operatively connected to a steam valve, 25 and, as far as I am aware, it has invariably been the practice to increase the steam pressure in the cylinders as the engine was overhauled by surges, jerks or overstrains in the towing hawser, and thereby build up 30 a high steam pressure in opposition to increases of stress in the hawser. This building up of steam pressure was coincident with the paying out of the hawser. Furthermore, when the hawser slackened it was 35 the practice to decrease the steam pressure in the engine cylinders which decrease took place coincident with the winding in of the hawser.

In the prior art machines it is usual to 40 operate with a normal steam pressure which is low, say from twenty to thirty pounds, in the cylinders, to support the normal hawser stress. When the hawser tightens or overstrains, the engine is overhauled by the 45 increased pull or load to which it is subjected, and the steam valve is then operated to build up the pressure in the cylinders to a point, say to from one hundred to one hundred and twenty pounds, which 50 results in the stress or pull of the hawser building up from a normal of about twenty thousand pounds to an extraordinary stress of say eighty thousand pounds or more. This has made it necessary to use hawsers 55 of large diameter—for instance, a steel

wire hawser of a diameter of two inches and more. The use of steel wire hawsers of large diameter demands the use of winding drums of very large diameter to prevent serious bending strains in the hawser 60 when wound onto and off the drum.

In my present invention, I contemplate an entirely different mode of operation from that above stated, and which may be described generally as follows: Instead of increasing the steam pressure to oppose an increase of hawser stress, as contemplated by the prior art, according to my invention any slight increase in the stress of the towing hawser is followed by an instantaneous 70 reduction of the steam pressure in the engine cylinders, thus permitting the hawser to be paid out as much as is demanded by the motion of the ships, and thereby prevent undue stresses in the hawser. When 75 the stress in the towing hawser decreases and the hawser slackens somewhat, according to my invention the pressure in the steam cylinders is increased and the towing engine thereby is caused to wind in the 80 hawser until the desired or normal tension or stress is restored thereto.

When employing an engine, according to my invention, I am able to prevent excessive stresses in the towing hawser, because any pull on the hawser which would result in an overstrain is immediately reduced by the lowering of the steam pressure, permitting the drum to pay out the hawser and thereby relieve the strain. In 90 other words, I am able to maintain practically a normal stress on the towing hawser under all conditions of towing. This results in being able to employ a towing hawser of small diameter—for instance, a 95 steel wire hawser of one inch, or one and a quarter inch diameter, and consequently a winding drum of reasonable dimension. I am also able to use a shorter hawser and because the hawser is light of weight and 100 short in length it may, and usually does, remain entirely out of the water when it offers no resistance to towing.

The invention consists in the novel construction and combination of parts to be 105 more fully described hereinafter and the novelty of which will be particularly pointed out and distinctly claimed.

I have fully and clearly illustrated my invention in the accompanying drawings to 110

be taken as a part of this specification, and wherein—

Figure 1 is a view in side elevation, partly in section, of a towing engine embodying 5 my present invention;

Fig. 2 is a plan view of the structure shown in Fig. 1;

Fig. 3 is a view in rear elevation of the structure shown in Fig. 1, certain parts being omitted for the sake of clearness;

Fig. 4 is a section view of a controlling or regulating valve for controlling steam supplied to the engine; and

Fig. 5 is a detail view, partly in section, 15 of regulating or adjusting means for the valve shown in Fig. 4.

Referring to the drawings by characters of reference, 1 designates generally a bed or base-frame consisting of a base-plate 2 adapted to be secured by any suitable means 20 to a deck-plate or other part of a ship structure (not shown). This base-plate 2 is provided with vertical side standards 3, 4, each preferably consisting of flanges on 25 opposite sides thereof, and extending longitudinally from front to rear of the same. The standards constituted by the flanges 3, 4, serve as supports for the engine frame, which supports the towing line drum, which 30 will now be described. This engine frame consists of a base 5 consisting of horizontal side frame members 6, 6, and front and rear transverse members 7, 8.

The frame 5 is provided with depending 35 lugs 5^a on opposite sides thereof and at points intermediate the front and rear of said frame, which lugs respectively project between the flanges 3, 4 of the standards on the base 1, and are connected thereto by 40 fulcrum pins 5^b, let through said flanges and lugs whereby the frame 5 is movably mounted upon the bed frame, which movement in the preferred arrangement shown is a rocking one—that is, the frame 5 may 45 rock on the pins 5^b under conditions to be presently described.

Mounted on the side frames 6, 6 are pillars 9, 9 carrying at their upper portions bearings 10, in which turns a horizontally disposed drum shaft 11 carrying a winding drum 12 having end flanges 13, 13, and provided at one end with a gear 14, by means of which said drum is driven through means to be presently described. Mounted on the 55 forward portion of the frame 5 are bearings 15, 15 in which are journaled the ends of a horizontally disposed driving shaft 16 extending parallel to the drum shaft 11 heretofore described. On the ends of the 60 driving shaft are crank disks 17 provided with crank pins 18 connected by pitmen, not shown but indicated by dot and dash lines 19, with cross heads 20 in turn connected to the piston rods 21, see Fig. 1, 65 of reciprocating pistons of engine cylinders

22. The driving shaft 16 also carries eccentrics 23 for operating the slide valves 24 for said engine cylinders, the connections between said eccentrics and slide valves not being shown but obviously will be understood and can be supplied by those skilled in the art. The power shaft 16 carries a pinion 25 which meshes with the gear 14, heretofore described, and serves to drive the drum or control it as will be presently described.

In the preferred embodiment of my invention, the rocking movement of the drum supporting frame due to the pull in the towing line, is resisted by the force of springs 26 preferably arranged between the forward ends of the bed plate 2 and the frame 5, said springs being each seated at their lower ends respectively in seats 27, in the bed plate 2, and having their upper ends located 80 in spring seats or sockets 28 in the under portion of the frame 5. The seats or sockets 28 may each contain a follower plate 29 adjustable by a screw 30 threaded in the frame 5, as at 31, whereby the normal height 85 of the forward end of said frame 5 may be adjusted to regulate the extent of the rocking movement of said frame 5, and the expansive force of said springs may also be regulated. The springs 26 are of sufficient 90 strength to exert their force to maintain the frame 5 at a determined distance above the plate 2, and this distance may be varied by adjustment of the bolt 30. Between the rear end of the frame 5 and the plate 2 are 95 provided cushioning springs 26^a seated in sockets 27^a, 28^a, in the base plate of the frame 5 respectively, said springs serving to cushion any sudden drop of the rear portion of the frame, which may result from 100 breaking of the towing line or sudden abnormal decrease of tension therein. Said springs 26^a also, in conjunction with the springs 26, serve to balance the engine supporting frame 5 on its pivots. The frame 5 105 is normally supported by the springs 26 with its forward end elevated, so that increases in the tension on the towing line will tend to rock the frame on its fulcrum against the resistance of the springs 26, and thereby depress the forward part of the frame a distance in proportion to the increase in the towing line tension; this movement being utilized to control the flow of 110 motive agent to the engine cylinders, so that the pressure in the cylinders will be decreased instantly when an appreciable increase of tension is imposed on the towing line. I will now describe the controlling 115 valve, the steam connections or supply thereto, and the means whereby it is operated due to movement of the frame 5 to control the steam pressure in the cylinders.

Through the base frame 1 is an opening 32 through which extends a steam supply 130

pipe 33 leading to a steam line from a steam generator (not shown). This pipe is connected by a pivot joint of any suitable type, indicated at 34, to a feed pipe 35 which in turn is connected to a throttle valve 36 of any suitable type and controlled by hand-wheel 37 to control the supply of steam. The outlet branch 38 of the throttle valve is connected to the inlet duct 39 of the casing 41 of a reversing valve forming part of the controlling valve structure. This reversing valve comprises a vertical casing 41 divided by a partition 42 into cylindrical chambers 43, 44; the latter being connected by oppositely disposed conduits 45 with the valve chests 24 of the engine cylinders, one of the said conduits being indicated in dotted lines in Fig. 4. In the chamber 43 is a cylindrical valveway having upper and lower sets of openings 46, 47 and intermediate openings 48 communicating respectively with annular steam-ways 49, 50, and 51, respectively. The way 51 opens to the main steam line supply pipe 39, the way 49 to the exhaust pipes 52 from the cylinder valve chests and the way 50 communicates with a port 53 leading to a cylindrical valve-way 54 opening at its upper end into the chamber 44 and at its lower end into a port 55 opening through the valve-way, heretofore described, into the exhaust chamber 56 of the valve casing, the latter also communicating with the exhaust passage 49, as shown in Fig. 4. The upper and lower ends of the valve chamber 43 are connected by means of the by-pass or exhaust chamber 56 by means of the ports 58 and 59, and the annular passages 60 and 61. The main exhaust connection is shown at 62. In the cylindrical cage 43 is arranged a double piston valve having heads 63, 64, connected by a reduced portion 65, the heads being so spaced that when the valve is moved the space between the heads will span either the openings 47, 48 or the openings 46, 48, so that in the first position the exhaust ports 52 of the cylinder valve chests 24 will be connected to the exhaust 62 of the casing on the one hand and the steam inlet 39 with the port 53 on the other hand, while in the second position the steam inlet 39 will be connected to the port 46 to reverse the flow of the steam to the engine cylinders, and the passage 47 will be connected to the exhaust. This piston valve is provided with an extension rod 66 extending through a stuffing-box 67 in the head of the valve casing, said rod being threaded through a hand-wheel nut 68 rotatably mounted on the casing, said hand-wheel being operable to shift the valve to either of the positions above set forth.

In the cylindrical valve-way 54 is a puppet valve consisting of a hollow shell having a head 69 normally located in the chamber 44 and adapted to coöperate with

the upper edge of the way 54 to control the flow of steam between the chamber 44 and the port 53. This hollow valve is formed at its lower end with an annular piston head 70 connected to the head 69 by a reduced stem 71 which permits passage of steam around said valve in passing from the port 53 to the chamber 44. The head 70 terminates at its lower end within the passage 55, so that the chamber 44 communicates with said passage 55 under conditions to be described presently. The puppet valve is normally urged toward its seat by an expansion spring 72 seated on said valve and a spring plate 73 having a part 74 slidably 80 in an opening 75 in the head of the casing and engaged by an adjusting bolt 76 threaded through the head of the casing and operable to regulate the expansive force of the spring. Arranged in the valve-way 54 beneath the head 70 of the puppet valve is a piston head 77 which is adapted to either engage the lower end of said head 70 to cut off communication between the chamber 44 and the passage 55, through the puppet 90 valve, or to be moved away from said head to leave free communication between said chamber and passage. This piston 77 is carried by a stem 78 having at its lower end an enlarged cylindrical portion 79 slidably disposed in the head 80. The portion 79 of said stem 78 is connected to a vertical threaded rod 81 having a spherical upper end, by a ball and socket joint. The rod 81 has a squared lower end 82 seated in a correspondingly formed seat 83 in the frame 5, to prevent turning of said stem, but permitting vertical reciprocation thereof. On this rod 81 is threaded a pinion nut 84 having a collar 85 straddled by a yoke 86 on 105 one end of a lever 87, the other end of which is fulcrumed, as at 88 on the frame 5. This lever 87 is formed with a longitudinal slot 88^a in which is slidably arranged a block 89, having pivotally connected thereto, as at 110 90, one end of a link 91, the opposite end of which is pivoted to the bed plate 2, as at 92. By this arrangement, it will be seen that whenever the forward portion of the frame 5 is lowered, the rear portion of said frame 115 will be raised, which will result in the valve casing 40 moving relatively to the piston head 77. In order to provide for the proper adjustment of the valve so that it will operate properly when the plate 5 raises and lowers, under the changes in tension of the towing line, the block 89 may be moved longitudinally of the slot 88^a in the lever 88 and held in position by means of adjusting bolts 93 engaging said block 89 at one end, 120 and having their opposite ends seated in sockets 94 in the end walls of said slot 88^a. Arranged parallel to the rod or stem 81 is a vertical shaft 95 carrying a pinion 96 in mesh with the pinion 84 on said stem, said 130

first-named pinion nut being of such length as to be in constant driving engagement with said pinion nut during all positions of movement or adjustment of the latter. On the 5 said shaft 95 is a beveled gear 97 meshing with a beveled gear 98 on one end of a connecting shaft 99, on the opposite end of which is a beveled gear 100 meshing with a beveled gear 101 on the lower end of a vertical shaft 10 102. On the upper end of said vertical shaft 102 is a beveled pinion 103 meshing with a beveled pinion 104 on a hand-operated shaft 105 provided with a hand-wheel 106 for revolving the same. This arrangement provides 15 means for the manual adjustment, regulation and operation of the puppet valve independent of the automatic means consisting of the rocking movement of the drum support, and particularly for the adjustment 20 of the valve when setting it for the desired inpulling power, so that the steam pressure will be properly regulated by the automatic control.

The construction and arrangement being 25 as above described, the operation of the invention is as follows: The towing engine is constructed and arranged to automatically take in and pay out the hawser, so as to maintain an approximately constant pull 30 thereon, which pull or tension can be regulated by the operator to a range of from, say five thousand to twenty-five thousand pounds or more. Suppose, for example, the engine be regulated so as to exert a pull of 35 twenty thousand pounds on the towing line at a pressure of one hundred and twenty pounds steam pressure in the engine cylinders, and the valves are in substantially the position shown in Fig. 4, when steam is 40 turned on through the throttle valve 36 the engine will revolve the drum to take up the towing line and will continue this winding operation until the strain on the towing line increases toward twenty thousand pounds. 45 During this winding operation the main frame 5 which supports the drum is held at its highest point above the base plate 1 by means of the springs 26. The springs 26 will have an initial compression due to 50 springs 26^a and will not be further compressed until the cable stress exceeds a determined amount. As the pull on the towing line approaches the determined amount, say twenty thousand pounds, said pull will serve 55 to gradually depress the drum support against the force of the springs 26; this downward movement or depression of the forward part of the frame will serve to lift the rear portion of the same and permit the 60 valve head 69 to seat and cut-off the supply of steam to the engine cylinders, and if continued the piston 77 will be hauled downward opening the cylinders to the exhaust. The steam pocketed in the cylinders will act 65 as a cushion only to the degree required, the

exhaust port being instantly closed when the resistance to paying out is reduced slightly below normal. It will be understood that the point at which the valve 69 closes is determined by the preliminary vertical adjustment of said valve relative to its seat through the operation of the hand-wheel 107 shifting the valve stem 81 by means of the nut 85. This operation, *i. e.*, closing of the valve, having taken place, the frame of the 70 engine normally maintains a position relative to the bed frame corresponding to the desired pull on the towing line, so that increases in the tension on the towing line will serve to further depress the drum frame 80 against the force of the springs 26, while decreases in tension will result in the force of the springs being exerted to lift the drum frame. Should the change of tension on the towing hawser be an increase, and the forward end of the frame consequently depressed, the rear end of the frame will be raised carrying with it the controlling valve 85 casing which will result in the valve head 77 being separated from the puppet valve head 90 70, the result being that the chamber 44 may be open to the exhaust port 55 if necessary, through the hollow puppet valve and the space provided between the lower end of the latter and the head 77, and the steam will 95 be permitted to escape from the engine cylinders, thus permitting the pull on the towing line to overhaul the engine without increasing the steam pressure in the cylinders, until the tension on the towing line drops to 100 the point determined whereupon the previously depressed springs 26 will raise the forward end of the frame and cause the controlling valve cylinder to move downward 105 to thereby cause the heads 70 and 77 to meet 110 and close communication between the chamber 44 and exhaust port 55 through the puppet valve, thus maintaining the steam in the engine cylinders at the required pressure to cushion the pistons and thereby maintain 115 the desired pull on the towing line. It will be understood that by operation of the hand-wheel 106 in either direction the connections between the frame and the puppet valve may be changed, so as to regulate the point at 120 which the controlling valve closes, so that the towing engine may be regulated to pull any amount within the limits of capacity of the engine. Supposing that a decrease in tension in the towing line takes place, the 125 springs 26 will raise the forward end of the drum frame and thereby depress the controlling valve, so as to cause the steam valve 69 to rise from its seat, so that the steam inlet 89 is open through the port 53 and the 130 valve-way 54 to the chamber 44, and the steam is permitted to flow into the engine cylinders to move the pistons therein to drive the drum in a direction to wind the rope thereon and restore the determined ten-

sion in the towing line. As soon as the desired tension is reached the forward portion of the frame is again depressed against the force of the springs 26 and the controlling 5 valve thereby elevated to shift the same relative to the valve stem 81 to permit the steam pressure and the spring 72 to close the valve. The description of the operation just given applies to the operation of the towing line 10 after the same has been connected to the tow, and it will be understood that in connecting up the towing vessel with the towed vessel that the automatic valve does not function. When it is desired to pay out the towing line 15 to connect it to the towed vessel, the hand-wheel 106 is operated to set the puppet valve to pull, say four thousand pounds, which raises the puppet valve from its seat and establishes communication between the chamber 43 and the port 53. The double-headed piston valve 63, 64, is raised to bridge the ports 49 and 51, thus communication is established between the steam supply and the conduits 54 for the cylinders, and also between 20 the exhaust 62 and the exhaust conduits 45 to the cylinders. The flow of steam is, therefore, reversed from what it is during the towing operation, and the engine may be operated to pay out the towing line. 25 If desired, the one or both of the disks 17 on the power shaft may be encircled by a brake band 107 operable by a foot lever 108 to retard operation of the driving shaft 16 when the towing line is being paid out. 30 In towing engines internal friction of the towing engine and its parts has hitherto constituted an important consideration which could not be disregarded, because it, together with the steam pressure, constitute 35 the two forces which oppose the hawser stress, but one of the advantages of my invention is that within reasonable limits this internal friction may be ignored. By way of explanation, suppose a towing machine 40 could be built which would be frictionless and that it would oppose a thirty thousand pound hawser stress at one hundred pounds steam pressure, in which case the only force opposing the hawser stress would be the 45 force exerted by the steam pressure. In actual practice, however, in an engine of the capabilities mentioned, about thirty per cent. of the force afforded by the steam pressure would be expended in overcoming the 50 friction in the machine, so that but twenty-one thousand pounds pull would be available to haul in the hawser. Should the hawser pull exceed twenty-one thousand pounds it might go as high as the theoretical 55 force exerted by the steam engine—*i. e.*, thirty thousand pounds, plus the force expended in overcoming friction—*i. e.* nine thousand pounds, which equals thirty-nine thousand pounds—that is, the hawser might 60 build up as high as thirty-nine thousand 65

pounds before it would overhaul the machine and could become slackened, which obviously would result in an extraordinary over-strain in the hawser which might result in the breaking of the latter. These 70 conditions cannot take place in my invention, because the steam pressure is immediately reduced in the cylinders as soon as there is an increase of cable stress above twenty-one thousand pounds. When the 75 hawser pulls beyond twenty-one thousand pounds the steam is reduced, the hawser is then opposed by the friction of the machine, say nine thousand pounds, and a reduced pressure of steam, say about twelve 80 thousand pounds. Then if the hawser pull slackens say to twenty thousand pounds, the valve closes and the steam pressure is again increased in the cylinders, causing the engine to wind up the hawser until its stress 85 is again raised to normal, whereupon it is held by the engine until there is either an appreciable drop or rise in the hawser stress. The advantage of this is apparent, because I am able to disregard the friction within 90 reasonable limits as the total force of the friction and steam pressure can never exist simultaneously in opposition to the hawser when the hawser stress builds up over the determined normal, inasmuch as the steam 95 pressure is immediately reduced whenever the hawser stress rises above normal and there is consequently no force but the friction plus the amount of steam pressure permitted to exist by the opening of the controlling valve in proportion to the degree to 100 which said valve is open.

What I claim and desire to secure by Letters Patent of the United States, is:—

1. In a towing engine, a drum adapted to 105 have a towing hawser wound thereon, drum bearings, a movable support for the drum bearings, said support being movable under changes of tension in the towing hawser, a motor for driving the drum, a 110 controller for the motor, and means whereby the movements of said support due to change of tension in the towing hawser operate said controller.

2. In a towing engine, a drum adapted to 115 have a towing hawser wound thereon, drum bearings, a movable support for the drum bearings, a motor for driving the drum, a controller for the motor, and means whereby the movements of said support operate 120 said controller to cause the motor to pay out the hawser when the tension on the latter increases, and to take up the hawser when the tension thereon decreases.

3. In a towing engine, a drum adapted to 125 have a towing hawser wound thereon, drum bearings, a movable support for the drum bearings, a fluid pressure engine for operating the drum, a valve controlling the supply of motive agent to the engine, and means 130

whereby the movement of said support operates said valve to increase the supply of motive agent to the engine when the tension on the hawser decreases, and to reduce the 5 motive agent when the tension on the hawser increases.

4. In a towing engine, a drum adapted to have a towing hawser wound thereon, drum bearings, a support for the drum bearings 10 capable of movement in two directions, a fluid pressure engine for operating the drum, a valve controlling the supply of motive agent to the engine, and means whereby movement of the support for the drum 15 bearings in one direction operates said valve to increase the supply of motive agent to the engine, and movement of said support for the drum bearings in the other direction decreases the supply of said motive agent.
5. In a towing engine, a drum adapted to have a towing hawser wound thereon, a 20 rocking support upon which said drum is mounted, a fluid pressure engine for driving the drum, a valve for controlling the 25 supply of motive agent to the engine, and means whereby the movement of said support in one direction operates said valve to increase the supply of motive agent to the engine, and the movement of said support in 30 the other direction decreases said supply of motive agent.

6. In a towing engine, a drum adapted to have a towing hawser wound thereon, drum bearings, a movable support for the drum 35 bearings, yielding means sustaining said support, an engine, a valve for controlling the supply of motive agent to the engine, and means whereby movement of said support against said yielding means operates 40 said valve to decrease the supply of motive agent.

7. In a towing engine, a drum adapted to have a towing hawser wound thereon, drum-bearings, a movable support upon 45 which said drum bearings are mounted, a yielding means opposing movement of said support, an engine, a valve for controlling the supply of motive agent to the engine, and connections between said support and said 50 valve whereby the valve is operated to decrease the supply of motive agent when the support moves against said yielding means.

8. In a towing engine, a drum adapted to have a towing hawser wound thereon, drum 55 bearings, a movable support for the drum bearings, a spring opposing movement of said support in one direction, an engine for operating said drum, a valve for supplying said motive agent to said engine, and means 60 whereby movement of said support against the force of said spring operates the valve to decrease the supply of said motive agent to the engine.

9. In a towing engine, a drum adapted to 65 have a towing hawser wound thereon, a

movable support for the drum, an engine mounted on said support and adapted to operate said drum, a base upon which said support rests, a valve for controlling said engine, and a connection between said valve and said base whereby movement of said support relative to the base operates said valve.

10. In a towing engine, a drum adapted to have a towing hawser wound thereon, a 70 rocking support for said drum, a spring opposing movement of said support in one direction, an engine mounted on said support and adapted to operate said drum, a valve 75 controlling the supply of motive agent to said engine, and a connection between said valve and a fixed point off the support whereby rocking movement of said support against the force of said spring operates said valve to decrease the supply of motive agent to said engine.

11. In a towing engine, a drum adapted to have a towing hawser wound thereon, a support for said drum fulcrumed at a point intermediate its ends, a spring opposing swinging movement of said support on its 90 fulcrum in one direction, an engine for operating said drum, a valve controlling the supply of motive agent to said engine, and means whereby movement of said support against the force of said spring operates the 95 valve to regulate the supply of motive agent.

12. In a towing engine, a drum adapted to have a towing hawser wound thereon, a rocking support upon which said drum is mounted, said support being movable in one 100 direction when tension on the tow line increases, a spring opposing movement of the drum in said direction, an engine for operating the drum, a valve for controlling the supply of motive agent to the engine, and means whereby movement of said support 105 operates the valve.

13. In a towing engine, a drum on which a towing hawser is adapted to be wound, drum bearings, a movable support for said 110 drum bearings, a motor for operating said drum, a controller for the motor, means whereby movement of said support under changes of tension in the towing hawser operates said controller, and means opposing 115 movement in one direction of said support when the towing hawser is subjected to an increase of tension.

14. In a towing engine, in combination, a drum adapted to have a towing hawser 120 wound thereon, a support for said drum fulcrumed on an axis parallel to the axis of rotation of the drum, a spring opposing the rocking movement of said support in one direction, an engine to operate the drum, a 125 valve for controlling supply of motive agent to the engine, and means whereby said valve is operated to decrease supply of motive agent when said support is moved against the force of said spring.

15. In a towing engine, a base, a supporting frame fulcrumed in a point intermediate its ends on said base, a drum mounted on said supporting frame, a spring between the base and said frame to oppose movement of the latter in one direction, an engine for operating the drum, a valve for supplying motive agent to the engine, and a connection between said valve and said base 10 whereby the valve is operated when said frame swings on its fulcrum.

16. In a towing engine, a drum adapted to have a towing hawser wound thereon, a rocking support upon which said drum is mounted to move with said support, a fluid pressure engine for operating the drum, and means whereby rocking movement of said support and drum controls said engine.

17. In a towing engine, a drum adapted to have a towing hawser wound thereon, bearings for said drum, means for supporting said bearings whereby the latter are movable laterally of the axis of rotation of the drum under changes of tension in said hawser, a motor for operating the drum, a controller for the motor, and means whereby movement of said bearings in one direction under an increase in tension of the hawser operates the controller to reduce the pulling power of the motor, and the movement of said bearings in another direction under a decrease of tension in the hawser operates the controller to increase the pulling power of the motor.

18. In a towing engine, a drum adapted to

have a towing hawser wound thereon, a fulcrumed support for said drum, spring means opposing swinging movement of said support on its fulcrum in one direction, an engine for operating said drum, a valve controlling the supply of motive agent to said engine, and means whereby movement of said support against the force of said spring operates said valve to control the supply of motive agent to said engine.

19. In a towing engine, movable drum bearings, a drum revoluble in said bearings and movable therewith, a motor, a controller for the motor, and means whereby the movement of the drum bearings operates said controller.

20. In a towing engine, a motor, a drum mounted in bearings whereby the axis of the drum is movable laterally, means whereby the said lateral movement under increases and decreases in pull of a hawser operated by said drum controls the motor to reduce the pulling power of the motor when the pull of the hawser increases, and to increase the pulling power of the motor when the pull of the hawser decreases.

In testimony whereof I have hereunto signed my name in the presence of two subscribing witnesses.

THOMAS SPENCER MILLER.

Witnesses:

ERNEST PULSFORD,
J. STOKES CARSWELL.

Copies of this patent may be obtained for five cents each, by addressing the "Commissioner of Patents,
Washington, D. C."

It is hereby certified that in Letters Patent No. 1,319,601, granted October 21, 1919, upon the application of Thomas Spencer Miller, of South Orange, New Jersey, for an improvement in "Towing-Engines," errors appear in the printed specification requiring correction as follows: Page 3, line 130, after the word "pinion" insert the word *nut*; page 4, line 1, strike out the word "nut"; and that the said Letters Patent should be read with these corrections therein that the same may conform to the record of the case in the Patent Office.

Signed and sealed this 18th day of November, A. D., 1919.

[SEAL.]

M. H. COULSTON,

Acting Commissioner of Patents.

Cl. 254—172.
